CONTAINER CLOSURE FLAP

Wallace H. Bracken, Rye, N. Y., assignor to Hartmann Trunk Company, Racine, Wis., a corporation of Wisconsin

Application July 8, 1936, Serial No. 89,509

2 Claims. (CL 190—41)

This invention relates to improvements in container closure flaps.

In various types of wardrobe trunks, containers, suitcases and the like, certain sections of the same are provided with flaps securable over the face of a section to protect, cover, conceal and segregate garments and articles in said section. With the advent of the so-called "hookless" fasteners it has been common practice to releasably join meeting edges of said flaps by a line of "hookless" fasteners and the practice has been to have said line of fasteners extend adjacent and parallel to a side edge of the container section, with the result that the slide fastener 10 is manipulated by moving it along the line of connection parallel to a section edge. It will be readily appreciated that with said prior arrangement, even though the container is closed, if said side be flexed or bulged slightly a tamperer or 15 pilferer can reach the slide fastener and easily manipulate it to release and open the closure flaps and thereby reach articles within said section of the container.

Recognizing this disadvantage inherent to the prior arrangements, especially when the same are applied to a container having readily flexible or distortable walls, the present invention seeks to overcome said objections by providing container section closure flaps and connecting means therefor which are arranged and constructed so that operation and opening of the same cannot be effected from limited crevices at any one side of the container section.

As a specific object of the invention a closure flap arrangement is provided wherein the lines of connection of the complementary flaps extend inwardly angularly from all side edges of the container.

Another specific object of the invention is to provide multiple complementary closure flaps for a container having meeting edges and connecting means therefor which extend away from an edge of the container and divergently relative to each other.

A further object of the invention is to provide three triangular complementary closure flaps for a container, with slide fastener means applied to the meeting edges of said flaps and arranged so that when the slide fasteners are in closing position the same are relatively close to one another and may be connected and secured by a lock.

A further object of the invention is to provide container closure flaps which are easily arranged and manipulated, which are neat and

attractive in appearance, which are inexpensive, and which are well adapted for the purposes described.

These and other specific objects and advantages will be apparent from the following detailed description.

A clear conception of an embodiment of the invention may be had by referring to the drawing accompanying and forming a part of this specification in which like reference characters 10 designate the same or similar parts in the various views:

Fig. 1 is a perspective view of a suitcase of the type equipped interiorly with the improved closure flaps for the suitcase sections; 15

Fig. 2 is a plan view of the suitcase in open position showing closure flaps for both sections thereof, said closure flaps in each instance being secured together in closing relationship;

Fig. 3 is a vertical sectional view through the 20 open suitcase on line 3—3 of Fig. 2;

Fig. 4 is an enlarged fragmentary view showing joined portions of a pair of adjacent closure flaps; and

Fig. 5 is a fragmentary detail sectional view 25 taken on line 5—5 of Fig. 4.

While the invention has been shown herein as being specifically applied to a certain type of suitcase, it will be apparent that the novel features are capable of more general application to 30 cases, luggage carriers and containers in general, and that the specific disclosure should not therefore be construed as an intent to limit the scope:

For sake of illustration the invention is illustrated in a suitcase such as is illustrated in Figs. 1, 2 and 3. The suitcase is of the type wherein the walls thereof are relatively flexible and includes a body section 10 and a wardrobe section 11. Said sections are hingedly connected together so as to permit the same to open out as in Figs. 2 and 3 or to be secured together in complementary closed relationship as in Fig. 1. The suitcase is provided with conventional handle means 12 for convenience in carrying the same, 40 straps or other suitable securing means 13 for holding the sections together in closed relationship, 45

When the suitcase or container is opened up each section is of U-shape in cross section and 50 the upper end thereof is open. For the purpose of releasably closing the open end of each section and for protecting, covering and maintaining the articles and garments in said sections in proper relationship, the improved closure flaps 55

are applied to the open portion of each section.

As will appear most clearly from Fig. 2, the closure flaps for the section 10, for instance, include a pair of similarly shaped triangular end flaps 14 and 15 and an intermediate flap 16 which is in the form of a truncated triangle. Each of the flaps 14 and 15 is foldably secured along its straight side edge to an upper wall portion of the section 10. The other edges of said flaps 14 and 15 are normally free. The intermediate flap 16 is foldably secured along its inner edge to the inner or rear wall of the section 10 as at 17 in Fig. 3.

The diagonally extending inner edges of the flaps 14 and 15 carry extension bands 18 which are adapted to be overlapped by the diagonally extending free edges of the intermediate flap 16. There is also secured along said diagonal edges of the flaps 14 and 15, adjacent the outer faces 20 of the bands 18 and inwardly of the free edges thereof, a line of "hookless" fastener elements 19 adapted to cooperate with lines of complementary "hookless" fastener elements 20 secured along the free diagonal edges of the intermediate 25 flap 16. Each row of "hookless" fasteners 19 is adapted to be engaged with the adjacent elements 20 on the flap 16 by a slide fastener element 21.

Assuming that the closure flaps 14, 15 and 16 are all secured together in closing relationship as in Fig. 2 and that it is desired to separate said flaps and open the same for access to the section 10, it is merely necessary to move the slide elements 21 in diverging lines toward the rear or inner end of the section 10, thereby disengaging the adjacent lines of "hookless" fastener elements; thereupon the two side flaps 14 and 15 may be turned over laterally of the case section, and the flap 16 may be folded rearwardly affording complete access to the section 10. When the section 10 is packed and it is desired to completely cover and protect the articles therein and to close the section, the outer edge flap 22 is first folded inwardly and then the flaps 14 and 15 are folded over the open end of the section 10, and lastly the intermediate section 16 is arranged as shown so that its outer edges slightly overlap the outer free edges of the end flaps. Thereafter the slide fasteners 21 are moved forwardly along the engaging lines of "hookless" fasteners to secure the same together, and after securement the two slide fastener elements 21 terminate at the forward end of the section relatively close together. The tabs or flanges 23 of these elements are apertured as at 24, and the same may be connected together by a snap pad lock 25 as shown in Fig. 2. When said elements are so locked together, operation of the same to open or release the flaps is of course prohibited.

The complementary section 11 of the suitcase is equipped with similarly arranged flaps 14', 15' and 16', and the same will not be described in detail. The abutting edges of said flaps are arranged with "hookless" fastener rows 19 and 20 as previously described and as shown in detail in Fig. 4. Slide fastener elements 23' traverse said abutting rows, and the same may be joined at their forward converged ends by a lock 25.

In the suitcase illustrated the body section 10 is adapted to contain miscellaneous garments and traveling paraphernalia while the section 11 has movably mounted therein garment folding

and draping means including one or more removable hangers 26 and a panel 27.

From the disclosure and description it will be apparent that the improved closure flaps are effective means for securely covering and closing the open ends of the suitcase sections. The utility of these flaps is obvious when the suitcase is open as they cover and protect the contents of each section, and furthermore, due to the arrangement of the slide fastener elements and locks, each section may be closed and the flaps locked against undesired opening, even when the case sections are open. Perhaps the greatest utility in the present invention resides in the particular arrangement of the flaps and lines 15 of "hookless" fasteners when the suitcase is closed as in Fig. 1. If the flaps were held in closed position by means of fastener elements extending parallel to any free edge of a case section, it can be readily understood that if a side 20 wall portion of the case were bulged or flexed, a tamperer might readily insert his finger into the crevice thus provided and manipulate the fastening means and thereby release the flaps and gain access to the contents of the section. 25 This contingency is absolutely prohibited by the present invention, and it has extreme usefulness when incorporated in a container having flexible walls. It will be noted that the joined edges of all of the flaps extend in diagonal directions relative to any side edge of a section. Therefore if access is gained to a section through any bulged or flexed crevice at a side portion, it will be impossible to manipulate the slide fasteners, even though the same are unlocked, to an extent sufficient to gain access to the section. 30 This is due to the fact that the operation of the slide elements must be on a line at an angle to any edge of the section, and the further the slide element is moved for opening purposes the further it will be from the crevice through which entrance was effected, and said operation sufficient to effect opening is precluded unless, of course, an entire wall of the case is mutilated.

With respect to all of the closure flaps, it 45 should be observed that the same may be formed of material which may be plied so as to present an outer surface or layer which is strong, tenacious, and weather and dust proof, while the inner surface, layer or ply may be of a suitable fabric to harmonize with the interior lining of the container. Incorporating this material on the inner surface of the flaps eliminates the need of additional protective or lining material on the surfaces which contact articles and garments in 55 the container.

From the foregoing description it will be apparent that the improved closure flaps for containers provide tamper-proof means when the container is closed, and they also provide effective means for closing sections of the container when the container is open, and for being locked in closing relationship. The flaps and closure means therefore are compact, simple and easily manipulated and arranged.

It should be understood that it is not desired to limit the invention to the exact details of construction herein shown and described, for various modifications within the scope of the claims may occur to persons skilled in the art.

What is claimed as the invention is:

1. In a container section having an open face, the edges of the container surrounding said open face being rectilinear, three flexible, complementary flaps for closing the same, each being fold-

ably secured along an edge to a side of the section, free edges of one of the flaps meeting a free edge of each of the other flaps, "hookless" fastener means along both pairs of meeting edges, said flaps when joined forming a quadrilateral figure with a pair of converging lines of severance, slide fastener elements movable along said fastener means and lines of severance, and a lock for joining the slide fastener elements at the converged ends of said lines adjacent one side of the container section.

5
10

2. In a container section having an open face,

the edges of the container surrounding said open face being rectilinear, three complementary flaps for closing the face of said section, free edges of one of the flaps meeting a free edge of each of the other flaps, "hookless" fastener means along both pairs of meeting edges, said flaps when joined forming a quadrilateral figure with a pair of converging lines of severance, and slide fastener elements movable along said fastener means and lines of severance.
